UNITED STATES PATENT OFFICE.

JAMES EUDY THIEM, OF RALEIGH, NORTH CAROLINA.

STOVE-DOOR.

No. 872,694.

Specification of Letters Patent.

Patented Dec. 3, 1907.

Application filed August 1, 1907. Serial No. 386,640.

To all whom it may concern:

Be it known that I, JAMES EUDY THIEM, a citizen of the United States, residing at Raleigh, in the county of Wake and State of North Carolina, have invented certain new and useful Improvements in Stove-Doors; of which the following is a specification.

This invention relates to stove-doors, and has for its object to provide a door having a vertical as well as a horizontal hinge connection so that a combined drop and swing door is had.

The invention comprises a novel hinge construction to be hereinafter described and claimed, reference being had to the drawing hereto annexed, in which—

Figure 1 is an elevation of the door in closed position. Fig. 2 is an elevation showing the door swung open sidewise. Fig. 3 shows the door swung open downwardly or in drop position. Fig. 4 is a section on the line 4—4 of Fig. 1. Fig. 5 is a section on the line 5—5 of Fig. 1.

In the drawings, 10 denotes the door-frame of a stove, oven, or the like. The door 11 is formed at its bottom corners with sidewise and horizontally presented pintles 12 and 13, respectively, and at one of the top corners of the door is an outwardly and vertically presented pintle 14.

The bearing for the pintle 12 is a bracket 15 in the face of which is a recess 16 to receive said pintle. The pintle 13 works in an opening formed in the head 17 of a stem 18 which is swiveled vertically in a bracket 19 on the door-frame. The bearing for the pintle 14 is a bracket 20 having in its face a recess 21 to receive said pintle.

The entrance to the recess 16 is contracted, and the pintle 12 is oblong in cross section, the width of its short side being slightly less, and the width of its long side being greater than that of said entrance. The pintle therefore cannot pass out of the recess until its short side is brought in line with the entrance, and the parts are so arranged that they assume this position only when the door is closed. By reason of this the pintle is retained in the recess when the door is swung open downwardly so that it cannot drop off its support accidentally, and the pintle can be removed only when the door is closed. The pintle 14 and the recess 21 are arranged in the same manner.

The door has a handle 22 at the top and a

handle 23 at the side. On the door-frame are stops 24 on which the door is supported when it is open in drop position.

In the recess 16 is a spring-finger 25 which engages the pintle 12 so that it will work tight in the recess when door is being opened to drop position whereby it is prevented from falling heavily. When the door is closed, its weight binds the pintle 14 against one side of the recess 21 and also pintle 12 to the bottom side of recess 16 which securely holds the door closed, thereby rendering an extra catch or latch at the top or side of the door unnecessary.

To open the door sidewise as shown in Fig. 2 it is lifted slightly and then pulled forwardly by the handle 23. The door is first lifted in order to bring the pintle 12 in line with the entrance to the recess 16 so that it may pass out of the same. The door then swings open, the pintle 14 turning in the recess 21, and the stem 18 turning in its supporting-bracket 19. To open the door to the drop position the door is pulled forwardly by the handle 22 to remove the pintle 14 from the recess 21. The door then swings on the pintles 12 and 13, the latter turning in the head 17 of the stem 18.

The bearing-brackets of the door can be cast integral with the door-frame, or they may be made separate and secured thereto in any suitable manner.

The hinge construction herein described is intended principally for the doors of stoves, ovens or the like, but it can also be applied to other structures in which a combined drop and swing door is desirable.

I claim:

1. The combination with a door-frame, of a door having a horizontal and a vertical hinge-connection therewith.
2. The combination with a door-frame, of a door having pintles at its lower corners and a pintle at one of its upper corners, a swiveled bearing for one of the lower pintles, and a bearing for the other pintles in which they are removably supported.
3. The combination with a door-frame, of a door having pintles at its lower corners and a pintle at one of its upper corners, a swiveled bearing for one of the lower pintles, and supporting brackets for the other pintles, said brackets having recesses in their faces in which the last mentioned pintles are removably seated.

4. The combination with a door-frame, of a door having pintles at its lower corners and a pintle at one of its upper corners, a swivelled bearing for one of the lower pintles, supporting brackets for the other pintles, said brackets having recesses in their faces in which the last mentioned pintles are removably seated, the entrance to the recesses being contracted, and the cross section of the pintles being oblong, said pintles being movable into and out of the recesses by their short sides, and their long sides being wider than the entrances.
5. The combination with a door-frame, of a door having pintles at its lower corners and a pintle at one of its upper corners, a swivelled bearing for one of the lower pintles, supporting brackets for the other pintles, said

brackets having recesses in their faces in which the last mentioned pintles are removably seated, the entrance to the recesses being contracted, and the cross section of the pintles being oblong, said pintles being movable into and out of the recesses by their short sides, and their long sides being wider than the entrances. 20

In testimony whereof I affix my signature in presence of two witnesses.

JAMES EUDY THIEM.
